WINDOW ALARM LOCK

Felix Gilbert, New York, N.Y., assignor to General Alarm Corporation, New York, N.Y., a corporation of Delaware

Filed Oct. 24, 1966, Ser. No. 4,407

Term of patent 14 years

(Cl. D10—10)

FIG. 1 is a top perspective view of a window alarm lock embodying my new design;

FIG. 2 is a side elevational view of the alarm lock of FIG. 1;

FIGS. 3 and 4 are end elevational views of my alarm lock; and

FIG. 5 is a rear elevational view of my alarm lock.

I claim:

The ornamental design for a window alarm lock, as shown.
